UNITED STATES PATENT OFFICE.

GUSTAV HUBERT, OF GRAND HAVEN, MICHIGAN.

VEHICLE-SPRING.

SPECIFICATION forming part of Letters Patent No. 225,384, dated March 9, 1880.

Application filed December 22, 1879.

To all whom it may concern:

Be it known that I, GUSTAV HUBERT, of Grand Haven, in the county of Ottawa and State of Michigan, have invented a new and useful Improvement in Carriage Spring-Platforms, which improvement is fully set forth in the following specification and accompanying drawings, in which—

Figure 1 is a side elevation of a light carriage with my spring-platform attached; Fig. 2, a plan of sub-gear, including king-plate; and Fig. 3, a sectional view of king-plate, showing head-block and end of reach.

The object of my invention is to furnish a device by which to add comfort to the person while driving, as well as to combine strength and utility with cheapness in cost of production.

In the drawings, A A is a bent wooden spring, fastened forward to the pillow-block by means of bolts, rear to the axle by clips, and which is backed from x to x with either leather or metal. This spring is continued by a steel coil-spring, B, which supports the rear end of the carriage-body, the other bearing of the body being secured by clip at C on spring A.

D is a reach made in common with the king-plate E, and which, at F, is furnished with fixed shoulder b, which bears against collar C, which is supported by braces d d upon rear axle, G.

From the shoulder b the reach is extended through spring f, behind which is nut g, governing the recoil of reach against spring f.

It will be seen that with the weight of the carriage-body upon the springs, aided by the weight of one or more persons, the whole combination yields easily, and places a strain upon the spring f, which, yielding in turn, lengthens the reach, while it adds its own to the elastic force already in play. Any sudden recoil or tendency of the forward axle to recoil upon the rear axle, as when the wheel encounters a sudden depression or obstacle in the road, is checked by the fixed shoulder b at F, while, through the responsive action of the whole combination, the action of the wheel produces no inconvenient jolting of the carriage.

Having thus described my invention, what I claim as new, and desire to secure by Letters Patent, is—

The bent wooden spring A A, in combination with the steel coil-spring B, the reach D, and king-plate E, substantially as shown and described.

GUSTAV HUBERT.
